(57) **CLAIM**

The ornamental design for a camera cover, as shown and described.

DESCRIPTION

Be it known that the inventor, Xin HOU, has invented a new, original, and ornamental design for a camera cover, of which the following is a specification, reference being had to the accompanying drawings, forming a part thereof. A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever.

FIG. 1 is a perspective view of a camera cover showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.
